PLATFORM TYPE SHOE

FOUNT E. CURTIS, MILWAUKEE, WIS., ASSIGNOR TO
UNITED SHOE MACHINERY CORPORATION, FLEMINGTON, N. J., A CORPORATION OF NEW JERSEY

Application January 9, 1946, Serial No. 640,040

3 Claims. (Cl. 36—19.5)

1

This invention relates to platform type shoes, the shoe herein illustrated being of the platform type.

An object of this invention is to provide a durable and comfortable shoe of this type.

In making the shoe of the present invention, an insole of the shape and substantially the size of the last bottom is made and covered on its inner face with sock-lining material, the material being cut enough larger than the insole so that the material, when laid across the edge face of the insole, will project a substantial distance beyond its outer face. The outer face of the insole is covered with a similar but somewhat smaller piece of material which may be, for example, Gem duck. These coverings are cemented, respectively, to the inner and outer faces of the insole, the marginal portions of the larger piece covering the inner face of the insole being laid across and cemented to the edge face of the insole, the portion projecting beyond the outer face of the insole being cemented to the marginal portion of the outer covering of the insole. Thus, about the periphery of the insole is formed an upstanding rib composed of two layers of material cemented together.

The insole thus prepared is assembled with an upper upon a last and the upper lasted in a usual manner, for example with tacks or staples. As illustrated, the upper is tensioned and secured in lasted position by tacks driven through the upper and rib into the insole.

The shoe may now be presented to an inseam sewing machine provided with a guide for a platform-cover strip, the cover strip, upper and rib of the insole being sewed together by a seam located at the base of the rib. The inseam may be trimmed and a platform sole laid on the shoe bottom, the platform being preferably the size of the shoe bottom including the seam. The platform-cover strip is laid over and secured, for example by cement, to the bottom of the platform, and an outsole cement-attached to the overlaid cover. As illustrated, the platform includes a wedge heel which also is covered by the cover strip.

In the drawings,

Fig. 1 is a sectional view of the insole;

Fig. 2 is a sectional detail of a shoe with the upper lasted to the insole;

Fig. 3 is a sectional detail of a shoe after a platform-cover strip has been attached to the upper and insole by an inseam;

Fig. 4 is a sectional detail of a shoe after the platform sole has been laid and the platform-

2

cover strip laid over upon the bottom of the platform;

Fig. 5 is a sectional detail of a shoe after attachment of the outsole; and

Fig. 6 is a side elevation of a completed shoe.

In making the shoe, an insole 10 of the shape and substantially of the size of the last bottom is prepared. Since the insole is to be completely covered, a wide variety of materials may be used. To enhance the comfort of the shoe, however, it is desirable to use a cushion material such as felt for the insole. An inner cover or sock lining 12 and an outer cover or reinforcement 14 are provided, the cover 12 being larger than the insole by the thickness of the insole plus the height of a usual sewing rib. The outer cover 14 is larger than the insole by the height of the sewing rib. The cover 14, since it is hidden in the completed shoe, may be of any strong fabric, such as Gem duck, or may be of the same material as the cover 12.

The cover 12 is cemented to the inner face of the insole 10 and to its edge face, its marginal portion being allowed to extend perpendicular to the outer face of the insole at least to the height of a usual sewing rib. The layer 14 is cemented to the outer face of the insole, and its marginal portion is cemented to the upstanding portion of the cover 12, thus forming a two-ply rib 16 about the periphery of the insole, a cross-section of the insole then appearing as shown in Fig. 1.

The prepared insole is secured to the bottom of a last 18, for example by tacks 20 (Fig. 3), and an upper 22 is assembled on the last. The upper is tensioned and secured in lasted position in any usual manner, for example by staples or by tacks 24 driven through the upper 22 and rib 16 and into the insole 10, as shown in Fig. 2. The shoe is next presented to a sewing machine, for example an inseam sewing machine such as that disclosed in United States Letters Patent No. 1,108,560, granted August 25, 1914, upon an application of Andrew Eppler, the machine being provided with a suitable guide for a platform cover strip 26 so that the cover strip is included in the seam 28 which also connects the upper 22 and the rib 16, as shown in Fig. 3. The inseam may now be trimmed but not so close as to endanger the strength of the inseam. The platform sole 30 is laid on the shoe bottom, as shown in Fig. 4, the platform sole being preferably of the size of the insole plus the thickness of the cover 12, the upper 22 and the platform cover 24. Since platform soles are usually of yielding material

such as felt, they can be compressed sufficiently in the platform laying operation to accommodate the inseam, though the margin of the platform may be reduced or rabbeted in the region of the inseam if desired. The cover 26 is laid over and secured, for example by cement, to the bottom of the platform, as illustrated in Fig. 4. A usual heel wedge may be attached to the platform and covered by the platform cover 26 which is, of course, in that case made wider at the shank and heel to cover also the wedge heel.

An outsole 32 is attached, as illustrated in Fig. 5, and may as usual be cement-attached to the overlaid portion of the cover strip 26. The shoe thus completed is represented in Fig. 6.

Having thus described my invention, what I claim as new and desire to secure by Letters Patent of the United States is:

1. A platform shoe having an upper, an insole, a platform sole, a platform cover and an outsole, said insole having covers on its inner and outer faces, said covers being larger than the insole and having their marginal portions united to constitute a sewing rib about the periphery of the insole, the upper and platform cover being sewed to said rib, the marginal portions of the platform cover extending over the bottom of the platform, and said outsole being attached to the marginal portion of the platform.

2. A platform shoe having an upper, an insole, a platform sole, a platform cover and an outsole, said insole having covers on its inner and outer faces, said covers being larger than the in-

sole and having their marginal portions united to constitute an upstanding sewing rib about the periphery of the insole, the upper and platform cover being sewed to said rib, the marginal portions of the platform cover extending over the marginal portion of the bottom of the platform, and said outsole being cement-attached to the marginal portion of the platform cover.

3. A platform shoe having an upper, an insole, a platform sole, a platform cover and an outsole, said insole having covers on its inner and outer faces, said covers being larger than the insole and having their marginal portions united to constitute a sewing rib about the periphery of the insole projecting outward at right angles to the bottom thereof, the upper and platform cover being sewed to said rib, the marginal portions of the platform cover extending over the marginal portion of the platform, and said outsole being attached to the shoe bottom.

FOUNT E. CURTIS.
